UNITED STATES PATENT OFFICE.

GEORGE RUSSELL WYATT, OF REDWOOD CITY, CALIFORNIA, ASSIGNOR OF THREE-EIGHTHS TO ALBERT MILES TAYLOR AND ONE-FOURTH TO THOMAS D. EVANS, OF REDWOOD CITY, CALIFORNIA.

OIL-BURNER.

936,206.

Specification of Letters Patent.

Patented Oct. 5, 1909.

Application filed April 15, 1909. Serial No. 490,097.

To all whom it may concern:

Be it known that I, GEORGE RUSSELL WYATT, citizen of the United States, residing at Redwood City, in the county of San Mateo and State of California, have invented new and useful Improvements in Oil-Burners, of which the following is a specification.

My invention relates to oil burners and 10 pertains especially to a burner and generator for use in cook stoves and the like.

The invention consists of the parts and the construction and combination of parts as hereinafter more fully described and claimed, 15 having reference to the accompanying drawings, in which—

Figure 1 is a longitudinal section of the invention. Fig. 2 is a plan view of the burner as applied. Fig. 3 is a cross-section 20 on the line X—X, Fig. 1. Fig. 4 is a section on the line Y—Y, Fig. 1.

The burner proper comprises a double ended tubular casing A, having symmetrical ends, and the ends closed by the caps 2, except for the small openings 3, through which 25 the inflammable gas generated in the generator 4 may escape into the fire box 5 and there be ignited.

Inside the burner casing is a combined 30 double ended valve and tip cleaner 6, which is reciprocal in the casing to move into or out of one or the other of the orifices 3, according to the direction in which the member 6 is reciprocated. The ends of member 6 35 are pointed, as shown, so as to fit the corresponding flared or concaved inner ends of the orifices 3.

The reciprocation of the member 6 to open or close, or to clean one or the other of the 40 orifices is done by appropriate means, as by a handle 7, supported in a tube 8, which latter screws into one side of the casing A. The inner end of the handle has a crank arm projection 9 to fit hole 10 in the member 6. On 45 the other end of the handle 7 is a hand-wheel 11 by which the handle can be rocked to move the member 6 back and forth.

The generator 4, which extends parallel 50 with the casing A has a suitable discharge into the burner between the ends of the latter. The other end of the generator extends outside of the fire box and connects with the oil supply pipe 12, through which the oil is fed either by gravity or pumped under suitable pressure.

The generator incloses a snug fitting plug 13, which has a nut portion 14, screwing into a T 15, into which the generator 4 and oil pipe 12 also screw. The top of the plug 13 when screwed into position has a longitudinal groove or trough 16, through which the oil flows toward the burner; the T 15 inclosing a suitable annular space through which the oil may pass around the plug 13 and flow thence through the generator confined in the comparatively narrow groove 16.

The object of plug 13, with the trough portion 16, is to reduce the size of the oil passage in the generator so that no considerable quantity of oil will collect therein 70 with the consequent danger of being rapidly converted into gas and causing a back pressure in the oil pipes and possibly result in explosion. Also, and what is more important, this trough with its large body of 75 metal, represented by the plug 13 and which is cooler than the top of the generator tube 4 nearer the flame, will operate to collect the asphaltum and other heavy non-volatilizing matters, the more volatile portions of 80 the oil being rapidly converted into gas and passing thence out through the orifices 3 of the burner. Without the use of the groove and plug 13, or some equivalent means for collecting the asphaltum and like heavier 85 residue, there is more or less tendency to soot, which is avoided to a great extent by my burner.

When the burner is installed in the fire box represented at 5, it is placed about centrally thereof and so disposed that a jet or flame may be directed from each end of the burner in opposite directions against an asbestos or other fire-proof wall or surface 17 at the ends of the fire box. The purpose 95 of these asbestos, or like fire-proof walls, is to arrest and spread the volume of the discharged vapor and effect a complete combustion of the same.

Since the orifices 3 are comparatively 100 small they have more or less tendency to clog, but by a small turn of the handle 7 the member 6 is shifted in one direction or the other to drive the sharp point of the member into the orifice and remove any 105 obstruction.

Since one end of the burner is directed over and in line with the generator the latter is maintained hot by the flame and consequently a suitable quantity of gas is gen- 110

erated for a continual supply to the burner. If only a small flame is needed, such as can be supplied by one or the other of the jets at either end of the burner, the handle 7 is turned to shift the member 6 and close one or the other of the orifices 3 whereby only half the amount of gas will be consumed. If a large fire is needed the member 6 is turned in a central position and leaves both 10 orifices 3 open.

Having thus described my invention, what I claim and desire to secure by Letters Patent is—

1. An oil burner comprising a double 15 ended casing each end of the casing having a gas outlet and a member having a needle point at each end reciprocal between said gas outlets, and operative alternately to close one outlet and open the other, or vice 20 versa, and means for reciprocating said member.

2. An oil burner comprising a double ended casing each end of the casing having a gas outlet and a member having a needle 25 point at each end reciprocal between said gas outlets, and operative alternately to close one outlet and open the other, or vice versa, and means for reciprocating said member, said last named means comprising 30 a handle having a crank arm projection engaging centrally of said member and a tubular guide connected with the casing through which said handle passes.

3. An oil burner consisting of a double 35 ended casing with a central perforated tip for each end of the casing, a needle pointed

member in the casing and operative to close one tip when moved in one direction and correspondingly open the other tip, and vice versa, means for reciprocating said member, 40 and a generator tube entering the casing between its ends, said generator tube extending parallel with the burner casing.

4. In an oil burner, the combination with a double-ended casing having gas outlets, 45 and means controlling said outlets, of a generator tube entering the casing between its ends and said generator tube extending parallel with the burner casing, and a solid plug in the generator tube substantially 50 filling the generator tube, except for a longitudinal groove at the top of the plug, and means for feeding oil in said groove.

5. The combination with a fire box of a double ended burner casing within the fire 55 box, said double ended burner casing having perforated end tips, a member reciprocating within the casing and having pointed ends to fit the perforations in said tips, means for reciprocating said member from a point 60 exterior to the fire box, and a generator arranged parallel with the burner casing and connecting therewith between its ends, said generator extending exterior to the fire box and connected with the oil supply pipe. 65

In testimony whereof I have hereunto set my hand in presence of two subscribing witnesses.

GEORGE RUSSELL WYATT.
